ACOUSTICAL DEVICE

Harry F. Olson, Collingswood, N. J., assignor to
Radio Corporation of America, a corporation
of Delaware

Application November 21, 1933, Serial No. 699,090

6 Claims. (Cl. 179—138)

This invention relates generally to devices for producing electrical currents which are dependent on and vary as the waves of sound and, more particularly, to readily portable microphones or sound pick-up devices which are responsive to the pressure of a sound wave.

A microphone responsive to both the velocity component and the pressure of a sound wave is disclosed in United States Patent No. 1,892,645 granted on an application of Julius Weinberger and myself. In accordance with this patent, the diaphragm of a ribbon microphone is rendered sensitive to sound wave pressure by placing the opening of a pipe or conduit in juxtaposition to a part of the ribbon diaphragm. The structure disclosed by the patent, however, is not suitable for microphones which must be readily portable such as those suspended from the coat lapel of a speaker.

In accordance with the present invention, the structure is simplified, the impedance presented to the ribbon diaphragm being rendered independent of frequency by means of a winding passageway which is formed at the back of the diaphragm, is filled with tufts of felt or the like and is enclosed within the magnetic structure of the device.

The principal object of the invention is to provide an improved microphone which operates in response to sound wave pressure and is of relatively light weight, thus permitting it to be suspended from the clothing of the user if desired. Another object is to provide a ribbon microphone which is of relatively light construction. A further object is to provide a ribbon microphone which responds to sound wave pressure.

The invention will be better understood from the following description when considered in connection with the accompanying drawing and its scope will be pointed out in the appended claims.

Referring to the drawing:

Fig. 1 is a partly exploded view of a microphone constructed in accordance with the invention.

Fig. 2 illustrates a preferred means of forming a winding passageway or labyrinth inside the magnetic structure of the device.

Fig. 3 is a plan view of the front of the device, and

Fig. 4 illustrates a modified form of the invention which is satisfactory from the viewpoint of performance but is less satisfactory from the viewpoint of compactness and portability.

The device of Figs. 1 to 3 includes a corrugated ribbon diaphragm 10 which is mounted in the field of a magnetic structure including a yoke 11

and pole pieces 12. To the rear of the diaphragm 10 and within the chamber formed by the magnetic structure is located a member 13 arranged to form a winding passageway or labyrinth. This passageway opens at the rear of the diaphragm 10 and may be loaded with felt filling 14 or tufts of felt for rendering the impedance presented to the diaphragm independent of frequency. It will be noted that the diaphragm 10 is suspended between the end pieces 15 which cover the upper and lower ends of the passageway.

As indicated by Fig. 4, the impedance chamber may be in the form of a pipe 16 flared at the end adjacent the diaphragm and extending linearly to the rear of the device. This structure, however, lacks compactness and possesses other serious disadvantages where portability is an important consideration.

Having thus described my invention, I claim:

1. The combination of magnetic field producing means arranged to form a single chamber, an electrical conductor forming a diaphragm and mounted in said field to form a section in the wall of said chamber, means covering the rear of the conductor and arranged to form a passageway leading from said conductor and within said chamber, and means located within said passageway for rendering said conductor responsive to the pressure of a sound wave.

2. The combination of magnetic field producing means arranged to form a chamber, an electrically conducting diaphragm mounted in said field to form a section in a wall of said chamber, means arranged within said chamber to form a winding passageway with one of its openings covering the rear of said diaphragm, means within said passageway for rendering the impedance presented to the diaphragm independent of frequency.

3. The combination of magnetic field producing means arranged to form a chamber, an electrically conducting diaphragm mounted in said field to form a section in a wall of said chamber, means including a sheet of material loosely rolled to form a passageway with one of its openings at the rear of said diaphragm, means within said passageway for rendering the impedance presented to the diaphragm independent of frequency.

4. The combination of magnetic field producing means arranged to form a chamber, an electrically conducting diaphragm mounted in said field to form a section in a wall of said chamber, means including a sheet of material loosely rolled to form a passageway with one of its openings at

the rear of said diaphragm and felt loosely filling said passageway.

5. The combination of magnetic field producing means arranged to form a chamber, an electrically conducting diaphragm mounted in said field to form a section in a wall of said chamber, means including a sheet of material loosely rolled to form a passageway with one of its openings at the rear of said diaphragm, felt loosely filling said passageway, and means closing the ends of said roll and forming the sides of said passageway.

6. The combination of magnetic field producing means arranged to form a single chamber, an electrical conductor forming a diaphragm mounted in said field, means arranged to form a labyrinthian passageway having its mouth adjacent said conductor and leading into said chamber, and damping means located within said passageway.

HARRY F. OLSON. 10
